UNITED STATES PATENT OFFICE.

BENJAMIN Q. P. FOSS, OF CHICAGO, ILLINOIS.

PORTABLE GAS-PRODUCER FOR LOCOMOTIVES.

1,156,399.

Specification of Letters Patent.

Patented Oct. 12, 1915.

Application filed March 22, 1910, Serial No. 550,918. Renewed April 19, 1915. Serial No. 22,497.

To all whom it may concern:

Be it known that I, BENJAMIN Q. P. Foss, a citizen of the United States, residing at Chicago, in the county of Cook and State of Illinois, have invented certain new and useful Improvements in Portable Gas-Producers for Locomotives, of which the following is a specification.

My invention relates to improvements in portable gas producer systems, and its purpose is to provide improved means and appliances for operating a portable gas producer in connection with a locomotive or marine boiler.

In the system herein described the producers utilize any form of hard or soft coal, and the crude producer gas is supplied directly to the locomotive from a car containing the producers and most of the other principal parts of my apparatus.

In order to fully explain the operation and advantages of my improvements I have shown the important features of a complete operative system.

My object is to burn the gas in its crude or unpurified form and the producer can be built with either an up or down draft. I prefer a down draft and have shown a producer constructed in this manner in the accompanying drawings, and have described it in the following specification. I have provided means for effecting a flow of the gas from the producer to the fire-box of the locomotive and have provided a burner in the locomotive and means for supplying the burner with the necessary air to support perfect combustion. I have also provided means whereby the current of gas may be diverted from the fire-box and burned above

the car during the short periods in which the locomotive is brought to a stop at stations or other points along the road. A small pilot light is kept burning immediately adjacent this overflow device. The overflow is thereby ignited and unpleasant odors arising from the unburned gas are prevented. Each producer is provided with a door at the top for charging it with fuel and for the admission of air. Steam connections are also made at the top for effecting the proper flow of steam through the fuel. The producers are provided with cleaning doors both above the grates and below them. Steam connections are also

made with the ash pit in order to permit the passing of a current of steam upwardly through the generator.

Although I have described my improvements as being applied to locomotive or marine boilers, I do not wish to be considered as desiring to limit their use to these fields, as I also use them in connection with stationary plants of various kinds, such as are used in heating office buildings, bake ovens, etc.

Further objects and advantages of my improvements will become readily apparent in the following specification, and the novel elements and combinations thereof will be more specifically pointed out in the claims.

The details of construction and mode of operation of my invention will now be described, reference being made to the accompanying drawings, in which—

The figure is an enlarged longitudinal section of the rear portion of a locomotive and the forward portion of a car, showing the essential features of my improvements and their operative relation to each other.

In the accompanying drawings I have shown my improvements as applied to a locomotive, though it will be understood that similar combinations of the essential features of my invention may be applied to marine boilers and others.

In the particular embodiment of my invention illustrated herewith, A represents the locomotive and B is the producer car which contains the greater part of the apparatus.

The car B is substituted for the tender which is commonly used in connection with locomotives.

In the locomotive the fire-box 15 may have the usual construction and, in fact, my apparatus may be applied to any of the ordinary forms of locomotives without material change in said fire-box, except a reverberating wall for the flame to strike before entering the boiler tubes. The burner 16 is inserted in suitable apertures in the walls 17 and 18 of the firebox and boiler. The burner 16 may be so mounted as to throw the stream of gas into the fire-box above the usual grate. The burner is provided with circumferential openings 19 for the admission of air to support the combustion of the gas. The current of gas passing through

the burner will cause the air to be siphoned into it through the said openings 19. This burner is fully described in my application for Letters Patent, bearing Serial No. 5 505,825, filed July 3, 1909, on gas burners.

I prefer to add the reverberating arch 18^a to the firebox for causing the gases to circulate about the interior of the fire box and to come into more intimate contact with the 10 crown sheet and walls thereof before entering the tubes.

The burner is supplied with gas through the pipe 20, in which is a controlling valve 21 having a hand wheel 22 within reach of 15 the engineer, a long stem 22^a being provided for the purpose of bringing the said hand wheel to a sufficient height.

The pipe 20 is provided with a hose 23 and coupling 24 for connecting with the 20 pipe 25 on the car, and a branch pipe 20^a, having a cap 20^b, for the attachment of a hand blower.

The car is preferably of steel construction, which will be more fully described later. 25 The pipe 25 leads to the blower or exhauster 26, which is driven by a small engine 27. This exhauster 26 will draw the gas through the pipe 28 and force it through the pipe 25 to the burner in the fire-box.

30 The pipe 28 is provided with a T 28^a which is joined to two sections of pipe 29 and 30, which lead through the valves 31 and 32 to the ash pits or lower portions of the producers 33 and 34.

35 The upper head of the producer is provided with an opening, through which the fuel is fed to the interior.

These openings are provided with suitable covers 41 and 42, which may be closed air 40 tight when the producer is left idle for a considerable length of time. In ordinary operation, however, these covers are left open to permit a suitable supply of air. A nozzle is inserted in the upper portion of 45 the producer, through which steam is admitted above the fire to mingle with the air as it is drawn through the coal bed. This nozzle is connected with a pipe 44 which leads to the boiler of the locomotive. This 50 pipe is provided with an equalizer 45 for the purpose of giving to the stream a suitable pressure and volume when it flows into the producer, proportional to the amount of pressure on the exhauster. The pipe 44^a 55 leads from the equalizer to the pipe 46, which in turn leads to the hose 47, the coupling 47^a and the pipe 48, which finally enters the steam space in the boiler 50 of the locomotive at 49.

60 A branch pipe 51 leads from the pipe 46 through the throttle valve 52 to the exhauster engine 27. Steam from the boiler 50 is therefore used to drive the engine 27. A branch pipe 46^a having a cap 46^b, is provided for the attachment of a pipe 46^c con-

nected with another boiler when starting. This would be desirable when the locomotive had no steam of its own.

An extension 44^b to the pipe 44 leads to a similar pipe 44^c, which supplies steam to the 70 upper portion of the second producer 34. Another branch pipe 53 is joined by the T 53^a to the pipe 44^a and leads to the two branch pipes 54 and 55 which enter the ash pits or the space below the grates in the producers. In these pipes 54 and 55 are valves 57 and 58 for controlling the steam admitted to said ash pits, for blowing out the ashes on the grates and cleaning the fires.

The ash pits of the producers are provided with doors 58 and 59. The space above the grates is also provided with doors 60 and 61. The interior of the producers is therefore entirely accessible for cleaning and repair.

85 In order to permit an overflow of gas from the pipe 25 during short periods in which the locomotive is brought to a stop at stations upon the road, an overflow valve or by-pass valve 64 is provided, which is connected to the pipe 25 by the branch pipe 62. This overflow valve 64 has the general nature of a safety valve and may be set to open at a low pressure, so that when the engineer closes the valve 21 the current is 90 then diverted through this safety valve to the open air. In order to prevent the unpleasant odors arising from the gas thus allowed to flow into the atmosphere, a small burner or pony light 63 is attached to the 95 said safety valve casing 64 below the valve therein. This small pony light is allowed to burn constantly and a small flame is constantly in close proximity to the outlet from said safety valve. The gases are thereby ignited as soon as they escape. This flow of 100 gas is only for a short time, because of the fact that the engine that runs the exhauster is nearly stopped by the operator when the gas is flowing more than is needed under 105 the boiler. This usually occurs on entering stations, and because of this fact the loss in fuel is very nominal.

110 In order to furnish a supply of air for supporting combustion of the gas when starting the burner when the locomotive is not in motion, I attach a branch pipe 65 to the pipe 20, said branch pipe 65 being attached to such part of the air-brake system as will supply the desired quantity of compressed air. This pipe may be connected to the main reservoir, or to the pipe leading from the air pumps to said main reservoir of the air-brake system. The pipe 65 is connected with a small pipe centrally disposed 115 in the pipe 20, from which the air discharges and induces the flow of gas into said pipe 20, from which the resulting mixture passes to the burner 16. The said gas is mixed 120 with the said stream of air and together the 125 130

air and gas flow through the aperture in plug at the end of the pipe 20. The said mixture of gas and air flows through the burner 16 and induces a further current of air through the circumferential channels 19. In the pipe 65 I have placed the hand valve 65^a in convenient reach of the engineer. When the engine is entirely cold or without steam in its boiler, the exhauster may be started by another engine, said other engine furnishing the steam in a manner similar to the common practice in oil-burning locomotives.

In connection with the producers 33 and 34 I have provided fuel magazines 66 and 67, which carry an additional supply of fuel for use in emergencies. These magazines are charged at the top through doors 100, and are connected with the producers by chutes 68 and 69, in which are suitable gates or valves 71 and 70 for charging coal into the producers.

In order to furnish sufficient air to the burner 16 to support combustion, I provide a flue 81, which I attach to the exterior of the fire box walls at their lower rear portions. This flue is provided with a damper, which, in ordinary running, may be opened to the position shown in the drawings, whereby a strong current of air is admitted to said flue. This current of air of course will be proportional to the speed of the locomotive. The body of the burner 16 may be wholly inclosed within this flue and receive all of its air therethrough in ordinary running, or take all further supply from the air brake system. When starting the burner, however, it may frequently be found necessary to use a supply of air from the air-brake system, which can be admitted through the pipe 65.

I have shown and described the burners as located at the rear of the fire-box, but they may be placed at the front of the fire-box if it is found preferable to place them there. When placed at the front of the fire-box, the natural draft produced by the movement of the locomotive will be sufficient, without the use of the air flue 81.

The operation and use of my improvements has already been largely referred to, and a brief outline of the same will be here given. It will be understood that both producers 33 and 34 are filled to their capacity with fuel and that the magazines 66 and 67 are also filled before starting a run. The locomotive operator, when beginning a run, may start the small engine 27, which drives the exhauster 26, by opening the valve.

This will produce a current of gas from the bottoms of the producers to the burner 16 in the fire-box. In case the locomotive is not moving, the operator may open the valve 65^a to a sufficient extent to supply the required amount of air from the air-brake sys-

tem to support combustion in the burner 16. The operator will, of course, open the valve 21 through means of the hand wheel 22. The small pony light 63 is started and will, of course, continue to burn as long as the exhauster 26 is in action. The operator may control the supply of gas to the burner by controlling the speed of the engine 27 by means of the small throttle valve 52. He can also regulate it to a greater or less degree by the valve 21.

The gage 49^a enables the operator to estimate the supply of steam that is flowing to the exhauster engine 27. He is thereby enabled to regulate said supply by means of the valve 49^b. A relatively permanent regulation of the supply to the exhauster engine 27 may be effected by the valve 52, while the ordinary control and variations of said supply for short periods while running may be effected by the valve 49^b.

When the locomotive is brought to a stop for a short time, it is advisable for the operator to stop the consumption of the gas in the fire-box to prevent an over-heating of the same and the generation of an excess of steam in the boiler. The continued production of the gas may be permitted during this short period and allowed to overflow through the valve 64. The small pony light 63 will ignite this overflow and prevent the unpleasant odors that would result from its contamination of the atmosphere.

A rate of combustion sufficient to produce the necessary gas in the producers is maintained by the supply of air that is admitted through the openings 40 in the upper ends of the producers. The production of gas is also properly controlled and regulated by the steam which is admitted through the pipe 44. A steam jet may be admitted to the ash pit below the fire-box as occasion may require. An upward current of steam through the fire-box may be effected occasionally in order to regulate the fire.

Each one of the producers 33 and 34 is made of sufficient size to have a capacity that will run the locomotive continuously. The other producer can then be disconnected by means of either of the valves 31 or 32 and cleaned or repaired.

When the supply of fuel in either of the producers is exhausted, the reserve supply in the magazines 66 or 67 may be introduced through the chutes 68, 69 by opening the valves or gates 70 or 71. It is, of course, at all times possible for the operator to observe the supply of coal in the producers through the charging doors 41 and 42 in the top thereof.

By referring more particularly to the figure it will be seen that I have arranged the various elements in the car B in such manner as to permit convenient access to all of the parts. I prefer to make the car entirely of

steel, with the middle portion extending below the end portions in order to provide as much room as possible for producers of large size. The reserve magazines 66 and 67 are preferably placed at the top of the car, extending the full width of the car, in order to permit sufficient room for the operators to pass beneath them.

While I have described more or less precisely the details of construction, I do not wish to be limited thereto, as I contemplate changes in form and the proportion of parts and the substitution of equivalents as circumstances may suggest or render expedient, without departing from the spirit of my invention.

I claim:

1. The combination of a locomotive, a car, a gas producer on said car, means connecting said gas producer with the fire box of said locomotive, means to diminish the flow of gas to said fire box when the steam consumption is small, and a normally closed overflow valve for said producer arranged to open when the flow of gas to said fire box is diminished.

2. The combination of a locomotive, a car,

a gas producer on said car, means connecting said gas producer with the fire box of said locomotive, means to diminish the flow of gas to said fire box when the steam consumption is small, a normally closed overflow valve for said producer arranged to open when the flow of gas to said fire box is diminished, and a pilot light adapted to burn constantly adjacent said overflow valve.

3. The combination of a locomotive, a car, a gas producer on said car, means connecting said gas producer with the fire box of said locomotive, means to diminish the flow of gas to said fire box when the steam consumption is small, a normally closed overflow valve for said producer arranged to open when the flow of gas to said fire box is diminished, a pilot light adapted to burn constantly adjacent said overflow valve, and an inclosing casing for said valve and light.

In testimony whereof, I have subscribed my name.

BENJAMIN Q. P. FOSS.
